UNITED STATES PATENT OFFICE

JOHN C. SCHOFIELD, OF LOS ANGELES, CALIFORNIA

LAUNDRY TOOL

Application filed January 12, 1929. Serial No. 332,036.

This invention relates to a laundry tool adapted for removing from tubs or other containers clothing which is saturated with hot water, the tool being constructed to enable the operator to perform this operation easily and effectively without exposing his hands to the hot water or hot suds in which the articles being laundered are submerged, and also without tearing or otherwise injuring the fabrics of which such articles may be made.

An object of the invention is to simplify the construction of a tool of this character and to provide a tool which will be an improvement upon other tools of the kind with respect to simplicity of construction, strength and durability, convenience of manipulation and lowered cost of manufacture.

A further object of the invention is to provide improved means for utilizing a single wire for constructing the principal parts of the tool.

Other objects and advantages may herein-after appear.

Referring to the accompanying drawings, which illustrate what is at present deemed a preferred embodiment of the invention,

Fig. 1 is a front elevation of the tool in the operative position.

Fig. 2 is a side elevation thereof in the same position.

Fig. 3 is a plan view looking down upon the tool in the position of Fig. 2.

Referring in detail to the drawings, this laundry tool consists principally of a single piece of heavy wire having two similarly formed looped portions 5 and 6, such looped portions each being deflected preferably at an obtuse angle with relation to the shank portion 7 of the tool. Each of said looped portions is thus arranged to extend in a plane which is parallel to but spaced apart from the plane occupied by the other.

The end portions of the wire are so directed as to overlap at the shank 7, the shank of the

tool thus consisting of the central run of wire 6^a, which is a continuation of one end of the loop 6, a side run of wire 5^a, which is a continuation of the loop 5, the other side of the shank consisting of a wire run 9 which also forms the central portion of the main wire. 50

In order to complete the shank portion of the tool, near one end of said shank portion the three wire runs are clamped together by means of a clip 10, and at the other end of said shank a like clip 11 is provided. The shank is further strengthened, if desired, by dipping the completed tool into a metallic plating substance which, in addition to enhancing the appearance of the tool and preventing rust, will also act as a solder to unite together the separate wire runs of the shank and to prevent the clips 10 and 11 from slipping. This dipping into the plating substance more effectively strengthens the tool by reason of the fact that the two outer runs of the wire shank contact with its central run throughout the entire length of the overlap. 60 65

As an aid to obtaining a more secure hold upon the clothes or other fabrics to be removed from the tub 12, the tip portion of the loop 6 is provided with an upturned nose 6^b and the tip portion of the loop 5 is likewise provided with a deflected nose 5^b. 70 75

In Fig. 2 the tool is illustrated in position for removing clothing or fabric 13 from a laundry tub 12. It will be seen that the tool is reversible and it therefore makes no difference which end thereof happens to be grasped by the operator. The looped portions of the tool are each adapted both to form a good hand-hold and to form a good means for lifting articles from the tub without tearing or otherwise injuring them. 80 85

What is claimed is:

1. A laundry tool having a body portion which consists of the central portion of a wire reinforced by rebent overlapping end portions of such wire, thus forming three 90

*

juxtaposed contacting wire runs, and spaced clips which bind together said central portion and overlapping end portions of said wire.

5 2. A laundry tool having a body portion which consists of the central portion of a wire reinforced by rebent overlapping end portions of such wire and means which bind together said central portion and overlapping end portions of said wire into three wire runs of which the two outer runs contact with the central run throughout the overlap, such wire portion of said tool being looped at each end of said body portion of the tool, the loops thus formed being disposed angularly with relation thereto.

10 3. A laundry tool having a body portion which consists of the central portion of a wire reinforced by rebent overlapping end portions of said wire, and means which bind together said central portion and overlapping end portions of said wire, thus forming a contracted central shank portion, the wire loop at each end of said shank portion being expanded.

15 In testimony whereof I affix my signature.
JOHN C. SCHOFIELD.
